W. E. WILLIAMS

DISK WHEEL

Filed Oct. 21, 1922

Patented Feb. 15, 1927.

UNITED STATES PATENT OFFICE.

WILLIAM ERASTUS WILLIAMS, OF WILMETTE, ILLINOIS, ASSIGNOR TO AMERICAN STEEL FOUNDRIES, OF CHICAGO, ILLINOIS, A CORPORATION OF NEW JERSEY.

DISK WHEEL.

Application filed October 21, 1922. Serial No. 596,037.

The object of my invention is to provide a demountable disk wheel that will have the least rim weight and the most secure fastening which I have found it possible to obtain. Reference will be had to the accompanying drawing in which Figure 1 is a front elevation of the wheel.

Figure 2 is a side sectional elevation. Figure 3 is a section through a portion of the demountable rim.

Figure 4 is a section through a portion of the rim showing a modified form.

Figure 5 is a section on the hub bolt circle.

In the drawing 1 indicates a rear wheel hub of an automobile, 2 a flange integral with the hub, 3 the ordinary brake drum, and 4 the tread seat of a demountable pneumatic tire rim of the quick detachable type, wherein the main rim member 4 is a continuous integral ring and 5 the snap ring which is seated in the usual gutter formed by the upturned flange 7 of the drop portion 8 of the rim member 4, the snap ring being transversely split at 9. The main rim member 4 is slightly thickened as shown at 10 to provide a surface slightly inclined to the outer surface of the main rim member as indicated more clearly in Fig. 3.

The main body or web of the wheel is composed of a disk having upon its margin a rearwardly turned flange 11 upon which seats the thickened portion 10 of the rim, which flange is connected with the main portion of the disk by an inclined flange 12 which bears against the rear inclined face of the drop portion of the rim provided with the gutter 6. This inclined portion 12 connects with the zone 13 of the disk, arranged at a slightly opposed inclination and constituting a peripheral portion of the wheel disk. The peripheral zone 13 merges into a forwardly concave zone 14, and this zone merges into a hub zone 15 which is substantially parallel to the median wheel plane and apertured at 16 to take over the hub barrel 1.

The wheel disk is rearwardly reinforced by a plate 17, which plate may advantageously be of non-circular and preferably rectangular form as the retention of the triangular corners, which would be cut away and wasted if the plate were made circular, obviously effects additional reinforcement of the disk over an area within regularly spaced boundaries farther from the center

of the same than would be the case with a circular plate made from the same metal blank. Moreover, the contact of such plate with the wheel disk over a non-circular area interferes with the amplification of nodal lines of vibration and by their dissipation tends to minimize noise in use. The outer margin of the plate bears firmly upon the disk, while a plurality of spaced pockets 19 are formed in the plate and bear against the rear face of the disk inwardly of the plate margin. Inwardly of the pockets 19 the plate is formed into a flat zone 20 which fits against the hub flange 2 in spaced relation to the disk, and still further inwardly the plate is dished into contact with the disk in a narrow zone 21. A plurality of radial depressions 22 are formed in the zone 20 of the plate as best shown in full lines in Fig. 2 and in dotted lines in Fig. 1. These depressions act as stiffening corrugations and spacers to sustain the disk and plate apart against the thrust or compression of the clamping nuts 23 of the stud bolts 24 which secure the disk and its reinforcement plate 17 in demountable fashion to the hub. The main disk and the reinforcing plate are welded or otherwise suitably connected at the zones 16 and 21 and in the region of 25 near the margin of the reinforcing plate.

A clamping flange for transmitting the load from bolts 21 around the hub zone is provided with its outer edge stiffened by curling as indicated by 26 and its inner portion stiffened by the swell 27 and with its main portion 28 in contact with the zone 15 of the main disk.

The reinforcing disk with its depressions 19 and 22 serve to compose a trussed construction between the parts without the use of other pieces and at the same time furnishes a very light and cheaply made structure.

The main disk with its flanges 11 and 12 seated under the portion 10 and inclined portion 8, furnish a very desirable seat for carrying the rim 4, and, in case the wheel is to be used only as a demountable wheel, the parts may be secured permanently together by the rivets 37, see Figure 4.

When the wheel is used as a demountable rim wheel I provide a side clamping ring having the marginal flange 29, body portions 30, and the inturned marginal edge 31, which is secured by a series of screws 32 passing

through the body 30 on the ring and screwed into nuts 33 fixed in the rear of the zone 13 of the main disk.

The narrow seat 10 of the rim 4 adjacent to the inclined portion 8 allows a snug fit for the rim on the disk and at the same time provides clearance space for the removal of the rim after it has been pried away from the close contact at 10, and with this surface 10 inclined slightly as is shown in Figure 3 the rim is easily removed from the disk however close the fit of these parts. The location of this surface, adjacent to the gutter of the rim serves to furnish strength where needed and facilitates in some measure the rolling of the section.

An angle valve 34 shown in dotted lines in Figure 2 has its orifice end 35 projecting at the front face of the wheel through a hole 36 in the disk and a corresponding hole through the ring 30, when a ring is used.

The medial plane of the wheel is indicated by the line 38 which passes approximately in the region of the zone 15 of the 25 main supporting disk.

What I claim is:—

1. In a vehicle wheel, a main supporting disk forming the web of the wheel, in combination with a reinforcing disk at the rear thereof joined to and terminating at a zone on the main disk in the region between the hub flange and the rim connection and spread apart from the main disk at intervals in the region of the bolt circle of the hub flange and stiffened across this space by portions of the secondary disk being embossed in radially arranged corrugations; in combination with a hub having a radially extending supporting flange and a series of clamping bolts passing through the main disc and the reinforcing disk and adapted to clamp those parts to the said hub flange.

2. In a vehicle wheel, a flanged hub, a circular disk on the hub, and a rectangular plate on the hub at the rear of the disk as a

reinforcement for the same outwardly from the flange of the hub.

3. In a vehicle wheel, a flanged hub, a circular disk on the hub, and a rectangular plate on the hub at the rear of the disk, 50 said plate being secured at its outer margin to the disk in lateral contiguity therewith and having inwardly of such margin a plurality of corrugations which bear against the disk as a reinforcement for the same. 55

4. In a vehicle wheel, a flanged hub, a disk on the hub, and a reinforcing plate on the hub at the rear of the disk, said plate being provided, near the center of the disk, with an annular series of corrugations bearing against the disk, and further from the center of the disk, with another annular series of corrugations out of radial alignment with those of the first series and also bearing against the disk. 60

5. In a vehicle wheel, a flanged hub having an annular series of attaching bolts, a centrally apertured disk on the hub, and a centrally apertured plate on the hub at the rear of the disk, the plate being joined 70 about its inner margin to the disk in lateral contiguity therewith and being spaced from the disk outwardly of such junction by an annular series of corrugations in the plate in the zone of the attaching bolts. 75

6. In a vehicle wheel, a flanged hub having an annular series of attaching bolts, a centrally apertured disk on the hub, and a centrally apertured plate on the hub at the rear of the disk, the disk and plate being joined together in lateral contiguity throughout two radially separated zones and being held apart between said zones by an annular series of corrugations in the plate arranged in alternation with the attaching bolts. 80 85

Signed at Chicago, in the county of Cook and State of Illinois, this 16th day of October, 1922.

WILLIAM ERASTUS WILLIAMS.
